(57) **CLAIM**

The ornamental design for an exercise support device as shown and described.

DESCRIPTION

FIG. 1 is a right side exploded isometric view of a first embodiment of exercise support device.

FIG. 2 is a back side isometric view thereof.

FIG. 3 is a back side elevation view thereof.

FIG. 4 is a front side elevation view thereof.

FIG. 5 is a left side elevation view thereof.

FIG. 6 is a right side elevation view thereof.

FIG. 7 is a top side view thereof.

FIG. 8 is a bottom side view thereof.

FIG. 9 is a partial side view of the exercise support device in use.

FIG. 10 is a right side exploded isometric view of a second embodiment of an exercise support device.

FIG. 11 is a back side isometric view thereof.

FIG. 12 is a back side elevation view thereof.

FIG. 13 is a front side elevation view thereof.

FIG. 14 is a left side elevation view thereof.

FIG. 15 is a right side elevation view thereof.

FIG. 16 is a top side view thereof.

FIG. 17 is a bottom side view thereof.

FIG. 18 is a partial side view of the exercise support device in use.

FIG. 19 is a right side exploded isometric view of a third embodiment of exercise support device.

FIG. 20 is a back side isometric view thereof.

FIG. 21 is a back side elevation view thereof.

FIG. 22 is a front side elevation view thereof.

FIG. 23 is a left side elevation view thereof.

FIG. 24 is a right side elevation view thereof.

FIG. 25 is a top side view thereof.

FIG. 26 is a bottom side view thereof; and,

FIG. 27 is a partial side view of the exercise support device in use.

The features shown in dash-dot lines in the drawing depict portions of the exercise support device and environment which form no part of the claimed design. The dash dot dash lines define the bounds of the claimed design and form no part of the claimed design.
